CLAIM

The ornamental design for a bottle, as shown and described.

DESCRIPTION

The patent or application file contains at least one drawing executed in color. Copies of this patent or patent application publication with color drawing(s) will be provided by the Office upon request and payment of the necessary fee.

1. Bottle

1.1 : Front

1.2 : Perspective

1.3 : Right

1.4 : Top

The design represents a stylized bottle with customized neck and base; the bottle has engraving depicting vineyards placed around entire perimeter thereof from the middle portion to the bottom of the neck.
